US00D982162S

(12) United States Design Patent (10) Patent No.: US D982,162 S
(45) Date of Patent: * Mar. 28, 2023

(54) PORTABLE OXYGEN CONCENTRATOR

(71) Applicant: Kunshan Songcan Electronic Commerce Co., Ltd., Jiangsu (CN)

(72) Inventor: Song Jiang, Shanghai (CN)

() Term: 15 Years

(21) Appl. No.: 29/850,650

(22) Filed: Aug. 22, 2022

(51) LOC (14) Cl. 24-02

(52) U.S. Cl.

USPC D24/164

(58) Field of Classification Search

USPC D24/164, 201

CPC B01D 53/0407; B01D 53/04

(57) CLAIM

The ornamental design for a portable oxygen concentrator, as shown and described.

DESCRIPTION

FIG. 1 is a perspective view of the portable oxygen concentrator showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent portions of the portable oxygen concentrator that form no part of the claimed design.
